DESIGN FOR A GOBLET OR SIMILAR ARTICLE

John C. Rosenmerkle, Moundsville, W. Va., assignor to Fostoria Glass Company, Moundsville, W. Va., a corporation of West Virginia

Application July 25, 1933. Serial No. 48,821

Term of patent 7 years

To all whom it may concern:

Be it known that I, JOHN C. ROSENMERKLE, a citizen of the United States of America, and resident of Moundsville, county of Marshall, and State of West Virginia, have invented a new, original, and ornamental Design for a Goblet or Similar Article, of which the following is a specification, reference being had to the accompanying drawing, in which—

Figure 1 is a top plan view of a goblet or similar article, showing my new design; Figure 2 is a side elevation of the same; and—Figure 3 is a section on line 3—3, Fig. 1.

I claim—

The ornamental design for a goblet or similar article, substantially as shown.

JOHN C. ROSENMERKLE.
